UNITED STATES PATENT OFFICE

JOHN McWILLIAMS STONE, OF ST. CHARLES, ILLINOIS, ASSIGNOR TO OPERADIO MANUFACTURING CO., OF ST. CHARLES, ILLINOIS, A CORPORATION OF ILLINOIS

SOUND REPRODUCING DEVICE

Application filed July 26, 1929. Serial No. 381,206.

My invention relates to sound reproducing devices, and has among its other objects the production of devices of the kind described that are neat and attractive in appearance, 5 efficient and satisfactory for use wherever found applicable.

A particular object of the invention is to provide a device of the kind described adapted to be supported from an overhead 10 support.

Another particular object of the invention is to provide an improved device of the kind described adapted to be positioned upon the walls of a room.

Many other objects and advantages will appear as this description progresses, reference being had to the accompanying drawings, wherein:

Figure 1 is a front elevation of a loud 20 speaker which embodies my invention;

Fig. 2 is a plan elevation of the improved loud speaker;

Fig. 3 is an enlarged section taken on line 3—3 of Fig. 1;

Fig. 4 is an enlarged fragmentary section taken on the same line as Fig. 3, and

Fig. 5 is a vertical sectional section taken through a loud speaker which embodies another form of the invention.

Referring for the present to Figs. 1 to 4, inclusive, wherein I have illustrated a loud speaker embodying a preferred form of the invention, the reference character 10 identifies a baffle or panel which is substantially 35 rectangular in form, although it is preferably provided with ornamental top and bottom portions 11 and 12, respectively. The panel 10 is provided with an aperture 14 in

which a grille 15 is preferably positioned. 40 Disposed in back of the opening 14 and carried by the panel is a loud speaker which is identified generally by the reference character 16. The loud speaker may be of any suitable construction, but in this instance is

of the electro-dynamic type, and comprises a diaphragm 17 which has a conical portion 18 actuated by a winding (not shown) disposed in an annular magnetic field (not shown) 45 the annular magnetic field being formed by

a magnetizing structure 20 which is carried by a ring 21 secured to the panel 10 by screws 23. A felt ring 24 is preferably positioned between the ring 21 and the panel 10.

Secured to the ring 21 by the screws 23 is a 55 housing member 27 which is preferably frusto-conical in form for a purpose presently to be described. The housing member 27 cooperates with the ring 21 to carry a plurality of felt rings 29 between which the periphery of the diaphragm 17 is positioned. Mounted upon the housing 27 is an input transformer 30 which has its second winding 60 electrically connected to the aforementioned winding (not shown).

Preferably positioned beneath the loud speaker 16 and also carried by the panel 10 is a means comprising a transformer 32 and a rectifying tube 33 for supplying direct current to the magnetizing structure 20. At 70 the lower end of the panel 10, and secured to the back surface thereof is a switch device 34, whereby the operation of the loud speaker is controlled.

Projecting from the rear surface of the 75 panel 10 at the upper end thereof is a bracket member 38 which is preferably triangular in form and is preferably secured to the panel 10 by a metallic bracket member 39, the bracket member 39 being secured to the 80 panel 10 by screws 40. It may be mentioned that the panel 10 and the bracket member 38 are preferably formed from wood, or some other relatively light material.

Secured to the bracket members 38 and 39 85 by nuts 42 is a screw-eye 44, whereby the panel may be suspended from an overhead support by any suitable means. In the preferred embodiment of the invention a wire 45, or the equivalent, is employed to suspend the panel from a ceiling, or any other overhead support in a room. Thus, in Fig. 3, I have indicated a ceiling 47 from which a screw-eye 48 projects, and the wire 45 has its ends secured to the screw-eyes 44 and 45 95 to suspend the panel and the apparatus secured thereto as a unit from the ceiling.

As best shown in Fig. 2, the improved device is preferably positioned in the corner of 100 a room. In Fig. 2, I have indicated the walls

of a room by dot and dash lines, and it will be noted that the triangular bracket 38 corresponds to the angle between the walls at the corner of the room. To prevent the bracket member 38 from marring the walls of a room, I preferably provide a buffer member 50 formed of suitable soft material, such as felt, or the equivalent, to engage the walls. For a like purpose, I preferably provide rabbets 52 in the vertical edges of the panel 10 and glue strips 53 of suitable soft material, such as felt, or the like, in the rabbets, the construction being such that the strips 53 engage the walls of the room and prevent injury thereto.

As will be evident from an inspection of Fig. 3, the improved device is constructed in such manner that its center of gravity lies in front of the screw-eye 44 and therefore 20 the panel 10 rests against the walls of the room and does not swing back and forth.

A function of the panel 10 is to serve as a baffle to prevent the sound waves projected from one side of the diaphragm from sup- 25 pressing the sound waves projected from the other side thereof. As the side edges of the panel are straight and vertical, they co-operate with the walls of the room to perform the same function and there is no material 30 interference between the sound projected from the two sides of the diaphragm even though the panel is relatively narrow.

In Fig. 5, I have illustrated another embodiment of the invention which comprises a 35 panel 10a preferably identical in construction to the aforementioned panel 10. The panel 10a is adapted to be suspended from an overhead support by means comprising a bracket member 38a which is rigidly secured 40 to the panel 10a by a metallic bracket mem- ber 39a. A screw-eye 44a secured to the bracket members 38a and 39a has the same function as the above described screw-eye 44. Disposed in back of an aperture 14a pro- 45 vided in the panel 10a is a loud speaker 100 of the magnetic type. In this instance the loud speaker 100 comprises a diaphragm 101 which has its central portion connected to an armature 122, the armature 122 being dis- 50 posed in the field of a permanent magnet 123. The magnet 123 is carried by a bracket 124 mounted upon a plate 125 which is rigidly secured to the panel 10a by bracket mem- bers 107.

55 While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as possible, in view of the prior art.

60 65 65 What I claim as new is:

1. A device of the kind described comprising an apertured baffle member, a loud speaker carried by said baffle member and having a diaphragm located at said aperture, means for suspending said baffle member from an overhead support, and yielding material at the edges of the panel for engaging and protecting the walls of a room on which said device may be placed. 70

2. A device of the kind described comprising a baffle member, a loud speaker carried by said baffle member, means for supporting said baffle member in the corner of a room, and means formed of relatively soft material and carried by said baffle member for engaging the walls of the room at said corner and protecting them from being marred by said baffle member. 75

20 25 3. The combination with a device of the kind described comprising a panel and a loud speaker carried by said panel, of a bracket projecting from said panel and equipped with flexible means for suspending said panel and loud speaker as a unit from an overhead support, said flexible means being attached to said device in back of the center of gravity thereof. 80

20 25 4. A device of the kind described comprising a loud speaker, a baffle supporting said loud speaker, said baffle having vertically disposed edges, means for supporting said device adjacent a wall, and yielding means at said edges for protecting and engaging said wall. 85

20 25 5. A device of the kind described comprising a vertically disposed panel, a loud speaker carried by the panel, a bracket projecting from the panel, and means secured to the bracket for supporting said panel from an overhead support. 90

20 25 6. A device of the kind described comprising a vertically disposed panel, a loud speaker carried by the panel, a bracket projecting from the panel, and flexible means secured to said bracket for supporting said panel from an overhead support. 95

20 25 7. A device of the kind described comprising a panel having vertically disposed edges, a loud speaker carried by said panel, a bracket projecting from said panel, means secured to said bracket for supporting said panel adjacent a wall, and yielding means at said edges for protecting said wall. 100

20 25 8. A device of the kind described comprising a panel having vertically disposed edges a loud speaker carried by said panel, a bracket projecting from said panel, yielding means secured to said bracket for supporting said panel adjacent a wall, and yielding means at said edges for protecting said wall. 105

20 25 9. A device of the kind described comprising a vertically disposed panel having an aperture therein, a loud speaker disposed in said aperture and carried by said panel, a bracket projecting from said panel, and 110

115

115

120

125

130

means secured to said bracket in back of the center of gravity of said device for suspending said device from an overhead support.

10. A device of the kind described comprising a vertically disposed panel having an aperture therein, a loud speaker disposed in said aperture and carried by said panel, a bracket projecting from said panel, and flexible means secured to said bracket in back of the center of gravity of said device for suspending said device from an overhead support.

11. A device of the kind described comprising a baffle, a loud speaker carried by said baffle, a transformer and a rectifier carried by said baffle for supplying direct current to said loud speaker, and means for suspending said device from an overhead support in a room to have said baffle co-operate with a wall of the room.

12. A device of the kind described comprising a baffle, a loud speaker carried by said baffle, a transformer and a rectifier carried by said baffle for supplying direct current to said loud speaker, and means secured to said device in back of the center of gravity thereof for suspending it from an overhead support.

13. A device of the kind described comprising a baffle having an aperture therein, a loud speaker mounted on said baffle and equipped with a diaphragm aligned with said aperture, and a bracket projecting from said baffle for suspending it adjacent a wall of a room above the floor thereof.

14. A device of the kind described comprising a baffle having an aperture therein, a loud speaker mounted on said baffle and equipped with a diaphragm disposed at said aperture, and means at the upper end of said baffle for supporting it in a room so that it co-operates with a wall of the room to prevent the sound waves projected from one side of the diaphragm from suppressing sound waves projected from the opposite side thereof.

15. A device of the kind described comprising a baffle having an aperture therein, and a loud speaker mounted on said baffle and equipped with a diaphragm disposed at said aperture, means for mounting said baffle adjacent a wall, said baffle being formed to co-operate with said wall to prevent sound waves projected from one side of the diaphragm from suppressing sound waves projected from the other side thereof.

16. A device of the kind described comprising a baffle, a loud speaker carried by said baffle and provided with a diaphragm, and means for mounting said baffle in a corner of a room, said baffle being shaped to co-operate with the walls of said room to prevent the sound waves projected from one side of said diaphragm from suppressing the

sound waves projected from the other side thereof.

17. A device of the kind described comprising a substantially rectangular baffle having vertical side edges, a loud speaker carried by said baffle, and means for supporting said baffle in a corner to have its vertical edges engage the walls forming the corner.

In testimony whereof, I have hereunto set my hand, this 3d day of July, 1929.

J. McWILLIAMS STONE.
